SLITTING MACHINE

John A. Aycock, Rock Hill, S. C., assignor to Rock Hill Printing & Finishing Company, a corporation of Delaware

Application December 13, 1943, Serial No. 514,143

6 Claims. (Cl. 164—65)

This invention relates to machines for slitting webs of cloth, paper, other fabrics and sheet materials into narrower pieces or strips, in some of which machines the pieces or strips as cut are usually wound or rewound simultaneously into separate rolls or bobbins, but not in all machines.

The particular type of such machines in which the present invention is more especially concerned is the kind in which the slitting of the material is done by what is known as "score cutting" or wherein a smooth, hard-surfaced, metal platen roll is used with circular cutter disks having either straight edges or piked or scalloped edges, and maintained in peripheral rolling contact thereagainst and under substantial pressure so as to effectively slit the web of material passed between the platen roll and the opposed cutter disks.

For properly effective operation of such machines it is essential that the surface of the platen roll be kept continuously smooth and unmarred throughout the entire working length thereof; but, in the usual general commercial use of the machines, the platen roll surface becomes scored and grooved annularly to an appreciable depth, so much that the cutting action of the cutter disks is seriously impaired and the edges of the disks not only become dulled more rapidly but are often marred to such degree that resharpening is difficult and in some instances quite impossible. In many instances the grooving of the platen roll surface also precludes readjustment for the same or different slitting operations. This necessitates frequent replacement of the worn platen rolls and cutter disks with new ones.

The required surface hardening of the platen rolls makes it impractical to refinish the ones so marred in use. Thus, due to the high cost of producing these rolls and impracticability of resurfacing them, it is very expensive in replacements of the same, to say nothing of the time and labor required in making the changes, together with the loss of production on the machine incidental thereto. Preservation of the cutter disks is also an important economical matter in the operation and maintenance of the slitting machines in proper working condition.

The present invention has for one of its objects to prolong the life of the platen roll and the cutter disks by a simple practical provision for minimizing wear on the same. To such end the invention consists primarily in imparting longitudinal movement to the platen roll during rotation of the same and across the cutter disks in contact therewith, this movement being recipro-

catory and at a relatively slow speed of travel as compared to the speed of rotation of the platen roll itself and that of the cutter disks so as not to disturb the lineal travel of the web material being cut or cause undue dulling of the cutter disks.

An illustrative but non-limiting adaptation of the invention is set forth with particularity in the following description in conjunction with the accompanying drawing, in which:

Fig. 1 is a schematic view illustrating a conventional type of slitting machine to which the present invention is adaptable;

Fig. 2 is a view, also more or less schematic, showing an application of the present invention to a slitting machine;

Fig. 3 is a fragmentary view illustrative of the usual scoring effect of cutter disks on the platen roll of a slitting machine; and,

Fig. 4 is a similar view illustrative of the smooth and unscored surface preservation of the platen roll by the use of the present invention.

Referring now to the drawing in detail and first more particularly to Fig. 1, the numeral 10 designates the platen roll of a slitting machine of the type, in the operation of which said roll 10 and a spaced-apart companion roll 11 are usually positively driven by conventional means (not shown) so as to rotate in the same direction and thus function as winder rolls for rotating the reels or bobbins 12 supported thereon and into which the respective strips of material are wound as they are slit on the machine.

In the type of machine illustrated the web of material 13 to be slit is taken from a supply or mill roll 14, around guide rollers 15, and thence around the platen roll 10, on which latter the web 13 is slit and the cut strips thence wound into the reels or bobbins 12 as just above described.

A series of cutter disks 16, in number corresponding to the number of slits to be cut in the web material 13, are rotatably mounted, each in a rockable support 17 which is positioned on a common supporting bar or member 18. The rockable supports 17 are spring pressed to hold the carried cutter disks against the platen roll 10 with force sufficient to effect the cutting of the web material passing between the platen and cutter disks. In the particular score cutting machine shown, the spring element 19 is of the leaf type and extends from the outer end of the cutter disk support 17 and bears at its outer end against an abutment 20. For regulating the tension and force of the spring 19 it is provided with an ad-

justing screw 21 at its outer end which bears against said abutment 20.

In the operation of the kind of machine illustrated in Fig. 1, the platen roll 10 is rotated positively under power and by its rotation with the slitted fabric wrapped partially therearound pulls the web of material from the supply roll 14 and also causes rotation of the cutter disks 16 that are pressed against the platen roll by the spring elements 19 as above described.

In as much as the platen roll 10 has heretofore been mounted to rotate in a fixed position, i. e., without longitudinal movement, and the cutter disks 16 also rotating in fixed position in contact with the platen, annular grooves 22 of substantial depth (see Fig. 3) are soon worn into the circumferential face of the platen notwithstanding the high degree of hardness of the roll surface. This is due to the fact that the cutter disks are also hardened to withstand the usage of the same, and that the cutter disks work under pressure against the platen sufficiently to effect the slitting of the interposed web of material. In addition to the pressure of the cutter disks 16 against the platen roll 10, the inherent abrasive qualities in some of the slitted web material 13 itself, causes such rapid scoring and grooving of the platen that the operation of the slitting machine has to be stopped frequently and a longitudinal adjustment of the platen roll 10 has to be made, or else an equivalent lateral adjustment is made of the cutter disks. Not only are the necessary adjustments difficult and time consuming in themselves, but the machine is out of productive service during the time.

In accordance with the present invention and without any alteration in the heretofore general structure and operation of the slitting machine, the only material change specifically is in a provision for imparting longitudinal movement of the platen roll 10 during its rotation in operation, such longitudinal movement being reciprocatory, i. e., back and forth across the cutter disks 16 that are pressed thereagainst in the regular way in the machine as heretofore constructed and operated.

A practical embodiment of the present inventive idea is illustrated more or less schematically in Fig. 2, which is a general representation of the working parts of the machine as directly coordinated and cooperatively concerned. In this illustration the numeral 23 designates the side frames of the machine. The platen roll 10 is journaled in the side frames, as at 24, in a conventional manner so as to be supported rotatably and at the same time be capable of moving longitudinally in its bearings. This platen roll 10 may be driven for positive rotation under power by any suitable means permitting longitudinal movement of the roll. As shown, an annularly grooved pulley 25 is fixed on the shaft extension 26 of the platen roll 10, the same to be driven by flexible belting (not shown) which yields laterally sufficiently to permit the longitudinal movement imparted to the platen roll during its rotation.

The platen roll 10 is normally urged longitudinally in one direction by a lever arm 27 which is pulled constantly toward the adjacent machine frame 23 by a spring element 28. By this provision the platen roll 10 is not only urged constantly in one direction by the spring element 28 and lever arm 27, but its opposite shaft extension 29 is also pressed constantly against the upper end portion of an actuator rock-arm 30, which latter

is cam-actuated to move the platen roll positively in the opposite direction longitudinally against the yielding force of the spring element 28. By this provision, also, there is no end-play or lost motion in the longitudinal reciprocation of the platen and no appreciable hesitation in such movement of the platen at the end of either stroke thereof, inasmuch as the rock-arm 30 is always held in working contact with the actuator cam.

At the end of the actuator rock-arm 30 opposite to that which bears against the end of the shaft extension 29 of the platen 10, is an antifriction roller 31 which bears against a cam member 32 which is fixed on a drive spindle 33. By rotation of the cam member 32 to move its low side from and its high side against the antifriction roller 31, a rocking movement is imparted to the rock-arm 30 that causes longitudinal movement of the platen roll 10 in the direction against the force of the spring element 28 as before stated. By the same token the spring-pressed lever arm 27 returns the platen roll in the opposite direction as the high side of the cam member 32 moves from and its low side moves against said antifriction roller 31.

The driving spindle 33 of the cam member 32 has a gear 34 fixed thereon which is driven from a driving pinion 35 through an intermediate chain 30 of speed reduction gears which are designated generally by the numeral 36. The driving pinion 35 is driven by a gear 37 fixed on the end of the platen roll 10, and to permit of longitudinal movement of said platen roll during its rotation and still maintain an inter-operating engagement between the gear 37 and pinion 35, the pinion 35 is elongated so that the gear 37 can slide in intermeshed engagement therewith.

The ratio of the gearing between the positively driven platen roll 10 and the cam-actuated means that controls the longitudinal reciprocation of the platen roll is such that the longitudinal movement of the platen roll is very slow as compared to the speed at which the platen roll is rotated. In general practice and for the slitting of fabric on the average, the speed of rotation of the platen roll 10 is such that the web material 13 travels over the platen roll at an approximate speed of 100 yards per minute, while the endwise travel of the platen roll is at an approximate speed of 2 inches in 15 minutes. This relative speed of rotation and longitudinal reciprocation of the platen roll is, of course, subject to variation in different machines and different characters of material to be slit thereon, as well as variations in the relative sizes of the platen rolls and cutter disks and the relative degrees in the hardness of these elements.

In the longitudinal reciprocation of the platen roll 10 in accordance with the usual general application of the present invention in slitting machines, and especially where a wide web of material is cut into a large number of very narrow strips, the operating provision may be for only a definite length of stroke, such as for example, 2 inches, in the reciprocation of the platen roll. Or else provided for a definite stroke at least slightly in excess of the distance between two cutter disks as spaced apart for the widest strip to be cut on the machine. But, in some instances, it may be desirable to vary the length of stroke of the platen, in which case, the rock-arm 30 may have an adjustable fulcrum pivot 38, a practical illustration of which is indicated in Fig. 2. As shown, the fulcrum pivot 38 is between a block

38 mounted longitudinally adjustable on the rock-arm 30 and a support 40 likewise adjustably mounted on the adjacent side frame 28 of the machine. A conventional means for adjusting and holding the block 38 in position on the rock-arm 30 and the support 40 on the side frame 28, may be as indicated in Fig. 2, wherein the elements 38 and 40 are respectively mounted on screws 41 which extend through threaded bores therein and are swiveled at their ends in lugs 42 on the rock-arm 30 or the side frame 28, as the case may be, so as to be rotated but held against longitudinal movement, said screws having squared or otherwise suitably formed protruding end portions 43 for the application of a suitable tool for rotating the screws at will. By rotating the screws 41 in their swiveled engagement in their respective supporting lugs 42, the block 38 or the support 40, as the case may be, is accordingly adjusted, and by adjusting both the block 38 and the support 40, the fulcrum pivot 38 can be changed to several different positions whereby to vary the length of longitudinal travel of the platen roll 10 within certain predetermined limits of over-all movement.

By the provision for imparting longitudinal movement of the platen roll 10 across the stationarily located cutter disks 16 during rotation of said elements, not only is scoring and appreciable grooving of the platen roll prevented and thus leaving the roll smooth surfaced as shown in Fig. 4, but dulling wear on the peripheral cutting edges of the disks 16 is greatly minimized, thus obviating the necessity of frequent resharpening of the cutter disks and appreciably prolonging the life of the same. In prevention of undue dulling of the cutter disks 10 a clean cut of the web material is obtained over a longer period of time in the slitting operation and this is of substantial advantage in the easy separation, removal and winding of the strips as cut from the web.

It is further noted that in addition to the prevention of scoring the platen roll surface by the longitudinal reciprocation of roll in accordance with the present invention there is no appreciable reduction in the diameter of the roll where such reciprocation occurs across the cutter disks.

The increase in the life of the naturally expensive platen roll is an important advantage of the present invention, to say nothing of the preservation and prolonging of the life of the cutter disks.

By the provision of the present invention wherein the longitudinal movement is imparted to the platen roll a much softer surfaced roll can be used without any grooving effect thereon. So, too, not only is less resharpening of the cutter disks required, but the disks may be made more blunt than heretofore required and yet effect a clean cutting of the web material on the platen, thus requiring less repairing and resharpening of the cutter disks and greatly increasing production on the machine.

The provisions of the present invention are applicable to slitting machines generally, and with minor (if any) modification can be applied to existing machines.

It is here further emphasized that while the specific illustration in the drawings is of a straight edged type of cutter disk, the invention is practically and effectively applicable to machines using either the straight edged or the piked or scalloped edge type of cutter disks or wheels, of which latter there are several different com-

mercial patterns, a representative type being illustrated in Fig. 5. In fact, the present invention is especially advantageous where cutters having the piked or scalloped edges are used, particularly because of the even greater difficulty in sharpening and resharpening of the same as compared to the straight edged kind. Moreover, the grooves such as heretofore worn in the platen roll surface by the piked or scalloped edge cutters are wider than the grooves caused by the laterally stationary working contact of the straight edged cutters against the platen roll.

It is still further noted that, within the purview of the invention, the reciprocatory longitudinal movement of the platen roll instead of being of constant definite length of stroke the same may be alternating in different lengths, but, of course, within the limits of a given maximum length of stroke, which variable movement can be attained in any conventional manner (not shown) such as for example, by accordingly varying the form of the hereinbefore described, cam element 32. So, too, substitution of means of different kinds and principles for that illustrated in the drawing for the general operation and control of the platen roll is contemplated. The invention, therefore, is not limited to the specific construction and arrangement shown in the accompanying drawing.

I claim:

1. In a web slitting machine, a positively driven rotary platen roll with circular cutters pressed peripherally thereagainst to be thereby rotated and slit web material passing therebetween, said platen roll being journaled for rotation in its mounting with provision for its longitudinal movement during rotation, spring-actuated means normally urging said platen roll in one longitudinal direction, cam-actuated means for positively moving said platen roll in the opposite longitudinal direction and against the spring force urging it in the other direction, and a speed reduction gearing between said platen roll and the cam-actuated means that moves said platen roll longitudinally whereby said cam-actuated means is positively driven by the platen roll in rotation and longitudinal reciprocation of the roll is at a very slow speed of travel as compared to the speed of rotation of the roll and thereby prevents scoring and grooving of the platen roll by the cutters.

2. In a web slitting machine of the score cutting type, a hard, smooth surfaced platen roll, a plurality of spaced-apart, peripherally cutter-formed, circular members pressed peripherally against said platen roll whereby to slit the web material passing therebetween, means for rotating said platen roll, and means for imparting longitudinal movement to said platen roll during its rotation and thereby prevent scoring and grooving of the roll by said cutters, said means for moving the platen roll longitudinally being actuated by an interposed reduction gearing driven directly by and from the platen roll whereby the longitudinal movement of the roll is at a slower speed of travel than the speed of rotation of the roll.

3. In a web slitting machine, a rotary platen roll, a score-cutting type of slitting means in which a circular cutter member is pressed peripherally against said platen roll to effect slitting of the web material passing therebetween, means for rotating said platen roll, and means for imparting a longitudinal reciprocation to said platen roll during its rotation whereby to prevent groov-

ing of the roll by said cutter members, said last named means including a rotating cam element, a rock-arm bearing against said cam element and also against an axial extension of said platen roll, and an opposed spring-actuated lever arm bearing against an opposite axial extension of said platen roll normally urging the roll longitudinally towards said rock-arm and maintaining the latter in bearing contact with the adjacent axial extension of the platen roll and with said cam element, and driving means interposed between said cam element and said platen roll whereby said cam element is rotated positively and at a speed proportionate to the speed at which said platen roll is rotated.

4. In a web slitting machine a rotary platen roll around which the web material is carried to be slit, said platen roll being slidably journaled for rotation, circular cutters pressed peripherally against and rotating with said platen roll to slit the web material as it is carried around said roll, and a cam actuated member connected with said platen roll to impart uniform reciprocatory longitudinal movement to the platen roll across the cutters during rotation and thereby substantially prevent grooving of said platen roll by said cutters.

5. In a web slitting machine, a rotary platen roll around which the web material is carried to be slit, said platen roll being slidably journaled for rotation, circular cutters pressed peripherally against and rotating with said platen roll to slit the web material as it is carried around said roll, means for rotating said platen roll, and a fulcrumed lever member associated with said platen roll and cam actuated to impart uniform reciprocatory longitudinal movement to the platen roll across the cutters during rotation and thereby substantially prevent grooving of said platen roll by said cutter.

6. In a web slitting machine, a rotary platen roll slidably journaled for rotation, circular cutter members pressed peripherally against said platen roll to effect slitting of web material passing therebetween, means for rotating said platen roll, and a fulcrumed lever member associated with said platen roll and cam actuated to impart uniform longitudinal reciprocation to said platen roll during rotation, and means for varying the point at which said lever member is fulcrumed with respect to said platen roll to vary the reciprocating stroke imparted to said platen roll.

JOHN A. AYCOCK.
